UNITED STATES PATENT OFFICE.

EDMUND C. RIPLEY, OF HOOPER, WASHINGTON.

DESIGN FOR A STICK-PIN, LAPEL-BUTTON, OR SIMILAR ARTICLE OF MANUFACTURE.

49,971.

Specification for Design.

Patented Nov. 28, 1916.

Application filed May 24, 1916. Serial No. 99,702. Term of patent 7 years.

To all whom it may concern:

Be it known that I, EDMUND C. RIPLEY, a citizen of the United States, residing at Hooper, in the county of Whitman and State of Washington, have invented a new, original, and ornamental Design for a Stick-Pin, Lapel-Button, or Similar Article of Manufacture, of which the following is a specification, reference being had to the accompanying drawing, forming part thereof.

The figure is a face view of a stick-pin, lapel button, or similar article of manufacture embodying my design.

I claim:

The ornamental design for a stick-pin, lapel button, or similar article of manufacture, as shown.

EDMUND C. RIPLEY.

Witnesses:

H. R. RUDD,
L. O. JONES.
